(57) **CLAIM**

The ornamental design for a packaging unit, as shown and described.

DESCRIPTION

FIG. 1 is a top right rear perspective view of the packaging unit showing my new design;

FIG. 2 is a top view thereof;

FIG. 3 is a bottom view thereof;

FIG. 4 is a right-side elevational view thereof;

FIG. 5 is a left-side elevational view thereof;

FIG. 6 is a top plan view thereof;

FIG. 7 is a bottom plan view thereof; and,

The broken line showing in FIGS. 1, 6, and 7 represents perforations so that the central rectangular portion may be removed.
